UNITED STATES PATENT OFFICE.

FREDERICK W. GORE, OF QUINCY, MASSACHUSETTS, ASSIGNOR OF ONE-FOURTH TO HARRY F. ASBURY, OF BROOKLYN, NEW YORK, AND ONE-FOURTH TO FRANK ASBURY, OF HUNTINGTON, NEW YORK.

ELECTRIC-ARC LAMP.

1,142,246.

Specification of Letters Patent.

Patented June 8, 1915.

Application filed January 7, 1905. Serial No. 240,098.

To all whom it may concern:

Be it known that I, FREDERICK WILLIAM GORE, a citizen of the United States, residing at Quincy, in the county of Norfolk and 5 State of Massachusetts, have invented certain new and useful Improvements in Electric-Arc Lamps, of which the following is a specification.

My invention relates to electric arc lamps 10 of that type wherein the upper carbon is fed by gravity on an abnormal increase in the length of the arc.

My improved lamp is constructed to obviate the chatter of the carbons and the consequent 15 flicker of the light.

One of the salient features of my new lamp is the fact that when the current is first turned into it both carbons are lifted a limited distance and remain in contact with 20 each other for a period, after which period the separation of the carbons is effected by lifting away the upper carbon from the lower until the arc is established, the lower carbon remaining in such raised position 25 during the subsequent operation of the lamp. A decrease in the operative length of the carbons, owing to consumption thereof, is compensated for by a gradual feed of the upper carbon, but assuming that the clutch 30 does not slip upon the upper carbon while current is flowing through the lamp, said upper carbon is not permitted to come into contact with the lower carbon during the normal period of service of the carbons, 35 whereby the flickering of the light is overcome and the arc is kept constant and practically unchanged so far as regards its luminosity and color.

The descent of the upper carbon is arrested, in the present invention, by the action of a clutch which is under the control of the starting coil or solenoid. A dash pot controls the upward movement of the solenoid plunger before and after the clutch becomes 40 operative, and after the clutch becomes operative, then a retardation device checks or controls the tendency of a continued uplift of the upper carbon. The retardation device, in conjunction with the dash pot, 45 counteracts, to a certain extent, the quick uplift of the upper carbon during the first onrush of the current. The weight of the upper carbon and its carrier is sustained by the clutch when the solenoid is energized, but

when the clutch is released from the upper 55 carbon, the retardation device supports the upper carbon and controls the movement thereof. Thus, during the descent of the upper carbon, in the subsequent operation 60 of the lamp to feed said upper carbon, the retardation device supports substantially the weight of the upper carbon and the carrier 65 therefor at such times when the clutch is released from gripping engagement with said carbon.

The retardation device for the upper carbon becomes effective in controlling the descent thereof when the clutch is released, but this device is so constructed that the feed of the carbon is so slow and gradual as to be 70 imperceptible to the eye. The clutch and the carbon controlling retardation device are so related that when the former is not gripping the carbon the latter is controlling its descent in such a gradual manner as to maintain 75 the arc practically uniform and steady, clear and bright at all times. Furthermore, this retardation device is so constructed that it will not be affected by changes in temperature due to the heating effect of the current 80 or the cooling action of the air; and, furthermore, this device compensates for any changes in the position of the carbon carrier when manipulated by the attendant in replacing a burned carbon by a fresh one. 85

My invention embraces, also, a novel lifting device in connection with the lower carbon carrier, and a retardation device for said lower carrier, said retardation device being designed to check and control any sudden or quick movement of the lower carrier when free to move. Such devices are combined with means for permitting their adjustment bodily in a lateral direction to allow the attendant to obtain access to the 95 lower carrier for replacing the carbons therein.

Further objects and advantages of the invention will appear in the course of the subjoined description, and the actual scope of 100 the invention will be defined by the annexed claims.

Reference is to be had to the accompanying drawings, forming a part of this specification, wherein like characters of reference 105 are used to indicate corresponding parts in all the figures.

Figure 1 is an elevation, partly in section,

of an arc lamp constructed in accordance with my invention. Fig. 2 is an enlarged vertical sectional elevation through the devices at the lower part of the lamp. Fig. 3 5 is a sectional plan view, in the plane indicated by the dotted line 3—3 of Fig. 2, showing the foot plate of the lamp in its normal position by full lines, and in an adjusted position by dotted lines. Fig. 4 is a detail view 10 in elevation, showing the locking device for the foot plate. Fig. 5 is another detail view in elevation, of the movable member of said locking device, shown by Fig. 4. Fig. 6 is a 15 detached view of one embodiment of means for preventing the accidental removal of the checking nut at the lower extremity of the lamp. Fig. 7 is an enlarged view, partly in elevation, and partly in section through the upper part of the lamp, illustrating the retardation device for the upper carbon. Fig. 20 8 is a sectional plan view taken in the plane indicated by the dotted line 8—8, of Fig. 7. Fig. 9 is a detail view through the piston of the retardation device for the upper carbon.

25 The general framework of the lamp consists of a top plate 1, a foot plate 2, an intermediate plate 3, vertical rods 4, a canopy or top 5, and a suitable housing or casing for the working parts at the upper portion of 30 the lamp, said housing or casing being herein shown as consisting of the members 6, 7, and 8, although the detail construction of the casing is not material and may be modified or changed at will. The hood 5, is attached to the top plate 1, in any usual or 35 preferred way, and the lamp is hung or suspended by means of a hanger 9, which may be connected to any suitable supporting device. The member 6 of the casing is shown 40 as being attached to the hood 5, and the member 7 is intermediate of the members 6 and 8, for the purpose of joining them one to the other, said intermediate member 7 of the casing being shown as having a flared 45 lower portion 10, which is adapted to inclose the upper part of the usual lamp globe 11. The intermediate plate 3 of the lamp-frame is connected by the rods 4 to the foot plate 2, and said plate 3 is designed to be connected 50 rigidly with the top plate 1 by suitable rods, (not shown).

55 The upper and lower carbons, of the usual or any preferred type, are indicated at A, B, respectively, and with each carbon is associated a carbon holder and a retardation device, the retardation device for the lower carbon B acting indirectly thereon through a 60 slidable frame. This slidable frame is herein shown as a pair of tubes 12, 13, and a plate 14, the end portions of said plate being provided with sleeves or bosses 15, which are fitted on the lower end of the frame tubes 12, 13, so as to be movable therewith. The rods 4 of the lamp-frame are shown as tubular, 65 and they extend through the tubes 12, 13, of

the slidable frame, said tubular members of the frame being fitted loosely on the rods 4, so as to be capable of a limited vertical movement thereon.

70 The movement of the slidable frame in an upward direction is secured by the expansive energy of coiled springs 16, two of which are preferably employed, although the number is immaterial. Said springs are housed or incased within the lower end portions of the tubular rods 4, and each spring is seated on a plug or block 17, which is movable endwise in one tubular rod 4 (see Fig. 2), each block 17 being adjusted by a threaded stem 18, which is provided with 75 an exposed knob 19, and is screwed into a female thread at the lower extremity of the tubular rod 4. The upper part of each spring 16 acts on a plug 20, which is 80 slideable in the tubular rod 4, and to this plug is attached a pin 21, the latter extending loosely through a slot 22, provided in the rod 4, said pin being secured in the sleeve 15 and to the lower portion of one tube 12, or 13, of the 85 slidable frame. It will be seen that the springs 16 are adapted to exert pressure in an upward direction on the pins 21, and the tubular members 12, 13, of said slidable frame, so as to lift the same, and the compression or pressure of said springs 16 may 90 be adjusted or regulated by turning the knobs 19 of the threaded stems 18.

95 The plate 14 forming a part of the slidable frame lies at a suitable distance above the foot plate 2 of the main lamp-frame, and this plate 14 carries the holder 23 for the lower carbon B and the holder 24, on which is seated the arc-inclosing globe 25. The lower carbon holder 23 and the globe holder 24 may be of the usual or any preferred construction, but as herein shown, the carbon holder 23 has a thumb screw 26, (see Fig. 1) 100 adapted to clamp the lower carbon B in said holder. The globe holder 24 is shown as being attached to the carbon holder 23 to 105 surround or inclose it, and the holder 23 is clamped by suitable devices 27 to the plate 14 of the slidable frame, whereby the carbon holder 23 and the globe holder 24 are movable up and down with said slidable frame. 110

115 The foot plate 2 is adjusted in a horizontal plane by a swinging movement, and said foot plate carries the retardation device for the lower carbon and the slidable frame. As herein shown, the foot plate 2 is provided 120 at one end with a short sleeve 28, said sleeve extending upwardly toward the plate 14 of the slidable frame and fitting loosely on one tubular rod 4 of the lamp-frame, whereby the foot plate 2 is pivotally connected 125 with a member of the lamp-frame for swinging adjustment on a vertical axis. The other end of this foot plate 2 is provided with a notch 29 (see Fig. 3), and when in normal position this notched end of the foot plate 130

is adapted to fit around the other tubular rod 4 of the lamp-frame, as shown by Fig. 2, said free notched end of the foot plate being held in its normal position by any suitable type of catch 30.

A short casing or housing 31, is secured firmly to the middle part of the foot plate 2 in a way to extend downwardly therefrom, and to the lower part of said casing 31 is secured a transverse pin 32. Against the lower open end of the casing 31 is fitted a holder 33 for the lamp globe 11, said globe being shown as having its lower flanged end seated upon the holder 33. A spring 34 is seated on the globe in order to hold it steadily in place, and this spring is adapted to be fastened on or connected with the casing 31 in a suitable way. The holder 33 is clamped in place against the lower end of the casing 31 by a nut 35, which is threaded on a stem 36 (see Figs. 2 and 6). The stem has an eye 37, through which passes the pin 32, the latter operating to connect the threaded stem 36 with the casing 31. It is evident that the nut 35 may be screwed on the stem 36 to firmly clamp the holder 33, between the casing and said nut, and to prevent the nut from working loose accidentally, I provide a locking dog 38, one end of which is fitted in a slot 39 provided at the lower exposed end of the suspended bolt 36. This lower end of the dog 38 is pivotally supported by a pin 40 in the lower exposed end of the bolt, and the dog has a shoulder 41, arranged to be presented below the lower end of the nut 35, as in Fig. 2. The dog is mounted in the slotted end of the bolt 36 to move or fall by gravity toward an inclined position for its shoulder to lie in the path of the nut, thus preventing the latter from working off the bolt, but said dog may be pressed inward so as to lie within the bolt 36, thereby permitting the nut 35 to be unscrewed from the stem.

The retardation device of the slidable frame and the lower carbon consists of a piston head 42, a cylinder 43, and an operative connection between said cylinder and the cross plate 14 of the slidable frame. The piston head 42 is anchored in a stationary position at the lower part of the lamp, while the cylinder 43 is adapted to travel with the frame plate 14. This piston head 42 may be constructed in any suitable way and of any appropriate material, but I prefer to use a plug of plumbago or graphite which is clamped by plates 44 to a stem 45, the latter being attached to the pin 32 fixed in the casing 31, whereby the piston head 42 is anchored in place. The cylinder 43 of the retardation device is open at its lower end, while its upper end is closed by a head 46, the latter being provided with a boss 47, and with an air inlet chamber 48. In the head 46 is a port 49, adapted to establish

communication between the chamber of the cylinder 43 and the chamber 48, and in this last mentioned chamber is a check valve 50, which is adapted to be drawn by suction downwardly and tightly against a seat for the purpose of closing the port 49 on the upward movement of the slidable frame and the lower carbon, whereby the retardation device operates to insure a slow steady movement to the slidable frame when the current is admitted to the lamp, said frame having a steady progressive movement and free from a jerky or irregular travel.

The means for connecting the cylinder of the retardation device with the frame plate 14 provide a detachable connection between said retardation device and the slidable frame so as to permit the retardation device to be adjusted with the foot plate 2 when the latter is swung in a horizontal path around the axis afforded by one of the tubular rods 4 of the lamp-frame, whereby the lower carbon holder 23 is exposed to permit the introduction or removal of the carbons. A thimble 51 extends downwardly from the frame plate 14, said thimble being in alignment vertically with the carbon holder 23, and in the thimble is a bayonet slot 52. A rotatable hollow plug 53 fits loosely in the thimble 51, said plug having a pin 54 arranged to play in the bayonet slot 52. The plug 53 is provided below the thimble 51 with a thumb wheel 55, which is normally exposed to provide for the convenient adjustment of the rotative plug, said thumb wheel being arranged to rest on the upper face of the foot plate 2. The rotative plug 53 is chambered as indicated by Fig. 2, and in this chamber is fitted the ball shaped head of a connecting stem 56, the shank of which extends below the thumb wheel 55, and is arranged to enter the sleeve 47, forming a part of the head 46 for the cylinder 43 of the lower retardation device, said stem 56 being attached to the cylinder head 46 by a transverse pin or key 57. The parts 53, 56, form the members of a ball and socket connection between the movable cylinder 43 of the retardation device, and the plate 14 of the slidable frame, thus compensating for any irregularities in the position of the retardation device to the slidable frame.

It is evident that the rotative plug 53 may be turned for the pin 54 to lie in the vertical leg of the bayonet slot, after which the slidable frame consisting of the parts 12, 13, 14, may be lifted by hand or otherwise, in order to withdraw the thimble 51 from the rotative plug 53, thereby uncoupling the lower retardation device from the slidable frame. By releasing the catch 30, the foot plate 2 may be swung in a horizontal plane, and with it travels the lower retardation device and the other parts at

the lower end of the lamp, thereby permitting ready access to be obtained to the carbon holder 23, for inserting or removing the carbons A, B. For restoring the parts 5 to their normal positions, the foot plate 2 is moved in an opposite direction so that its notched end 29 will fit around one of the tubular rods 4, said end of the foot plate being engaged by the catch 30. The slidable 10 frame is now lowered for the thimble 51 to fit over the rotative plug 53, the pin 54 of said plug sliding into the vertical leg of the bayonet slot 52, after which the plug is turned for the pin 54 to enter the horizontal 15 arm of said slot, whereby the parts are connected operatively so that the lower retardation device will control the upward movement of the slidable frame and the carbon holder.

20 Within the thimble 51 is an insulating plug or washer 58, which fits tightly in the rotative plug 53, and is adapted to support the carbon should it drop accidentally, said plug 58 serving when the carbon is, through 25 carelessness, dropped accidentally upon it, to insulate the carbon electrically from the retardation device at the lower part of the lamp.

By reference to Fig. 2 it is to be noted 30 that the lower carbon carrier 23 is insulated electrically from plate 14 by vertical screws, the latter being provided with thumb nuts 27. The screws pass through suitable apertures in parts 23, 14, and through insulating 35 materials positioned between said parts 14, 23, and between these last named parts and the binding nuts 27, so that there is no metallic connection between parts 14 and 23.

I will now proceed to describe the devices 40 for feeding and controlling the movement of the upper carbon A, one of which devices, hereinafter termed the clutch, is effective normally in checking or arresting the downward movement of the carbon when 45 the current flows through the lamp, while the other device, hereinafter termed the upper retardation mechanism, acts to automatically control the downward movement of said carbon when released from the first 50 device, or clutch, such control of the upper carbon insuring an exceedingly slow and steady feed movement, but which is sufficient to compensate for the consumption of the carbon by the burning of the arc.

55 The electrically actuated means for clutching the upper carbon A are similar in many respects to some types of electrical lamps. The current is admitted at the positive binding post 59 and is conducted to and through 60 a resistance coil 60, the latter enveloping an insulating drum 61, preferably of porcelain, and attached to the top plate 1 or the hood 5, in any suitable or preferred way, said resistance coil being contained within 65 the part 6 of the housing. Supported with-

in the part 7, of said housing are the starting coils or solenoid 62, in which works the legs of a yoke shaped armature 63, and with this armature is associated a suitable clutch rod 64 (indicated by dotted lines in Fig. 70 1), which clutch rod controls the clutch 65, that is adapted to impinge on the upper carbon A. The clutch and the devices for checking or locking the upper carbon A, together with the magnet or solenoid 62, are 75 ordinary in the art, so that I do not consider it necessary to particularly illustrate and describe the same. With the checking devices for the upper carbon is associated a dash-pot, the position of which is indicated 80 at 66, and which is adapted to hold in check the movement of the armature when the current is allowed to pass through the coils of the solenoid. In the absence of this dash-pot a sudden rush of the current would 85 cause the armature 63 to be drawn into the magnets with great force and rapidity, if no provision had been made to control its movement. It is to be understood, therefore, that the dash-pot in the lamp operates 90 as a check and provides an elastic resistance to the force developed by the magnets.

As shown more particularly by Figs. 7, 8 and 9, the retardation device consists of an elongated tube 67, a piston head 68, and 95 means whereby a vacuum is established in the upper part of the tube 67 on the descent of the piston head 68. Said tube 67 is suspended flexibly from the top plate 1 of the lamp-frame by a ball and socket connection 100 therewith, and as shown, I employ a bolt 69 as the operative connection between the retardation tube and said top plate. A boss 70 is provided on the top plate for the reception of an insulating plug or washer 71, 105 the latter being clamped to the top plate by a gland 72, which is screwed on the boss 70. The hanger bolt 69 passes through and is secured in the insulating washer 71, so as to be electrically insulated from the metallic plate of the lamp-frame. The lower end portion of the hanger bolt 69 is formed with a rounded or globular head 73, which is fitted in a socket of a coupling member 74, the latter being externally threaded and 110 screwed into a female threaded chamber 75, which is provided in a head 76. This head is externally threaded and screwed into a female threaded upper end portion 77 of the retardation tube 67, and the head 76 is further provided with a chamber 78 and a 115 port 79, said port establishing communication between the chamber 78 and the piston chamber 67 of the tube 67. The bottom portion of the chamber 78 is fashioned to serve as a valve seat adapted for the accommodation of a ball or check valve 80, the latter being fitted loosely in the chamber 78, and intended to close the port 79 against the ingress of air on the downward movement 120 125 130

of the piston head 68, thereby establishing a partial vacuum in the piston chamber 67^a, and insuring a very slow movement to the piston head and the carbon A, which is movable therewith.

For regulating the effective area of the port 79 and the inlet of air to the piston chamber 67^a, I have provided another valve 81, which I will designate as a regulating valve to distinguish it from the automatic check valve 80. The sole function of the regulating valve 81 is to vary the area of the port 79 in head 76 so as to regulate the flow of air through the port when the piston head 68 is reciprocated in the tube 67 of the retardation device. This regulating valve has a tapering face adapted to be adjusted quite close to or in contact with a valve seat, which is provided at the lower extremity of the port 79, and said regulating valve is carried by a bridge plate 82, the latter being in one piece with a plate or washer 83, that is screwed into the upper threaded part of the retardation tube 67. Said washer 83 lies below and is independent of the head or closure 76 for the retardation tube, and said closure 76 together with the washer 83 may be screwed into the retardation tube so that the parts 76, 83, have such relation one to the other, that the valve 81 will provide an air passage of the proper area to permit the flow of air in the desired volume.

The current admitted to the resistance coil 60 flows through the magnet 62, and is supplied to the carbon by means of conductors 84, 85. The conductor 84 leads from one of the coils of the magnet 62 and is attached to the retardation tube 67, below the washer 83, which carries the regulating valve 81, the connection being made through an insulated bushing 86. The conductor 85 is coiled loosely in the piston chamber of the retardation tube 67 and it provides an operative connection between the conductor 84 and the upper carbon, so as to permit said carbon to descend with the piston head 68 without interrupting the communication between the conductor 84, and said upper carbon. The current passes through the piston head 68 from the conductor 85 to the upper carbon by means which I will now describe.

The piston head 68 of the upper retardation device is constructed, to have a moderately tight frictional engagement with the tube 67, so that it will at the same time be capable of a feed movement governed by and responsive to the adjustment of the valve 81, for the purpose of controlling the gravity movement of the carbon A when it is released from the clutch. I prefer to make this piston head 68 from a solid block of plumbago or graphite, and of the required dimensions to fit moderately tight within the tube 67, but to prevent the current from expanding, cracking or otherwise injuring

this block, an air space is provided around the bolt 89. The bushings 87 are clamped to the end portions of the block by the plates or washers, 88. A bolt 89 passes through the block, and to the upper end of said bolt is attached an end portion of the conductor 85. The other end of the bolt has a ball-shaped head 90, which fits in the socket of a coupling member 91, said member being secured in the upper part of a tubular carbon holder 92, for the upper carbon A. This holder 92 is shown as having elastic jaws adapted to frictionally engage with the carbon A, for the purpose of holding it in place, and within the carbon holder is a washer 93. The head 90 and member 91 form a ball and socket connection for the carbon holder 92 with the piston head 68, thus permitting the operator to turn the carbon holder 92 freely without affecting the position of the piston head 68 within the retardation tube 67, whereby the manipulation of the carbon holder by the attendant in removing and replacing a carbon will not disturb the cooperative position of the parts.

The arc inclosing globe 25 is fitted to a seat which is provided on a plate 94, said plate having insulating sleeves 95, arranged to fit on the tubes 12, 13, of the slidable frame, whereby the globe 25, as well as the lower carbon B, are supported wholly by the slidable frame.

The lamp should be provided with conductors and other accessories, such as are commonly supplied to ordinary arc lamps of this type to insure the operation of the parts.

As before indicated, the positive wire leading from a source of electrical supply, (not shown) is connected with the positive post 59, and similarly the negative wire is connected with the binding post 59^a. The current on entering the lamp passes through the resistance coil 60, and thence through the magnet 62, which it energizes, whereby the armature 63 is drawn upwardly into the magnet. On the initial movement of this armature the clutch is operated for the purpose of raising the upper carbon A. As the combined weight of the armature, the clutch rod and the dash-pot is removed from the slidable frame, the springs 16 act on the slidable frame, so as to impart an upward movement thereto, and to the lower carbon, B. The lower retardation device operates on the slidable frame to preclude any sudden and uneven movement of the lower carbon, while the springs act to impart movement to said frame and the lower carbon at a speed required to keep the two carbons in contact. The springs 16 are so adjusted that they cause the slidable frame and the lower carbon to rise a prescribed distance, and when this distance has been traveled by said frame and the lower carbon, the upward

movement of the frame and the carbon is arrested by pins 21 reaching the upper ends of slots 22 in frame rods 4.

It will thus be seen that the lower carbon 5 and the frame are lifted by the springs so that said lower carbon is raised simultaneously and in contact with the upper carbon. During such elevation of the two carbons, the clutch for the upper carbon is under the 10 checking action of the dash pot, the upper carbon is under the checking action of the upper retardation device, and the slideable frame and lower carbon are under the checking action of the lower retardation device, 15 all the parts acting in harmony and insuring a steady upward movement to both carbons.

At the completion of the uplift of the frame and the lower carbon under the action 20 of the springs, upper carbon, A, and with it the carbon holder 92 and the piston head are still drawn upward by the operation of the armature 63, and this continued upward movement of the upper carbon causes a 25 separation of the carbons to take place, whereby the arc is established between the two carbons. Owing to consumption of the carbons, the current weakens in the magnet 62, thus causing said magnet to have less 30 attractive force until the clutch releases its grip on the upper carbon A, whereupon the control of this carbon is transferred from the clutch to the retardation device, consisting of the tube 67 and piston head 68. 35 When the retardation device is brought into service the piston head 68 descends slowly in the tube 67, until the decreased distance between the two carbons causes the magnet 62 to regain its former power, and when the 40 magnet again becomes operative, the clutch is thrown into service so as to arrest a further descent of the carbons. It will be understood that when the clutch releases its grip on the upper carbon, the load or weight 45 of said carbon is transferred from the armature to the piston head and the retardation tube. Contact of the upper carbon with the lower carbon during the operation of the lamp is precluded by the retardation 50 device, for the reason that a partial vacuum is produced in the chamber 67^a above the head 68, and the external air exerts pressure against the under side of the piston head, thus overcoming, when the strength of the 55 field of the magnet is decreased, a sudden drop of the upper carbon into engagement mechanically with the lower carbon.

From the foregoing it will be understood 60 that in striking the arc, the two carbons, A, B, move simultaneously, the lower one, B, following the upper one and remaining in contact therewith so as to form a closed path for the flow of the current, but when said carbons are raised a certain distance, 65 then the lower one is arrested while the

upper one continues to move upwardly until the arc is struck. In the operation of the lamp subsequent to the establishment of the arc, the lower carbon is held in its raised position by the springs acting on the lower 70 slideable frame, while the upper carbon is controlled by the solenoid and clutch, and by the upper retardation device. This control of the upper carbon precludes it from coming in mechanical contact with the lower 75 carbon so long as the flow of current is uninterrupted through the lamp. When the carbons burn away, the strength of the current in the solenoid is decreased by the resistance of the arc, which results in releasing the clutch from carbon, A, whereupon the upper retardation device operates to allow the gradual downward feed of said carbon until the current again flows with the required strength through the carbons 80 and across the arc, and when the arc is restored the clutch is operated to lock the upper carbon. In striking the arc I accomplish my object by keeping the carbons A, B, in their normal contacting positions a sufficient period of time to allow the armature 85 63 to be drawn upwardly into a strong magnetic field, developed by the magnet 62, before a separation of the two carbons can take place.

In an arc lamp, the term "dash pot" is applied, ordinarily, to a device attached to or associated with the armature, core or plunger of a solenoid, the function of such a dash pot being to check and control the 100 movement of the armature, core or plunger more especially upon the first admission of current to the lamp. The numeral 66 indicates the position of such a device in the present lamp. When current enters the 105 lamp, the clutch being free from the upper carbon, the upward movement of armature 63 is first checked by the dash pot 66 which operates to so control the upward movement of the armature that it ascends slowly. As 110 the armature ascends, the clutch becomes operative, and by gripping the carbon, carries it upward, the result of which action is to compress the air in the retardation tube above the piston head 68. This upward 115 movement of the carbon compresses the air in the upper part of the retardation device, and there is no sudden and powerful impulse to check, owing to the action of dash pot 66, which operates on the carbon independently of the retardation device during 120 the upward travel of the carbon when current is first admitted. At this time, or during this operation, the upper carbon rests directly upon, and is supported by, the 125 lower carbon, and the latter is in turn attached to the lower retardation tube 43 and the slideable frame 12, 13. When the weight of the armature and the clutch is suddenly removed from tripping platform 94, there 130

is a tendency for the lower carbon to be forced upward suddenly by the expansive energy of coiled springs 16. This tendency is counteracted by lower retardation device 43. Now, since the weight of the upper carbon alone is not sufficient to hold the lower carbon down, it is raised slowly while resting upon the lower carbon. It is apparent that 5 slideable frame 12-13 and the springs 43 cooperating therewith constitute means for imparting motion to the lower and the upper carbons which are in contact with each other and upon the first admission of current to the lamp, such movement continuing 10 until the lower carbon and the upper carbon shall have traveled a predetermined distance, at which time the armature continues to ascend, the result of which is to pull the upper carbon upward, thus striking 15 the arc. It is obvious that dash pot 66 cannot affect the operation of the lower retardation device. The solenoid pulls the armature upwardly, checked by dash pot 66 and the slideable frame 12-13, relieved of the 20 weight of the armature and actuated by spring 16 will be lifted so as to force the upper carbon upward a predetermined distance. Accordingly, it is apparent that the slideable frame bears a portion of the total 25 weight of the armature, the clutch and the two carbons when said frame travels a certain distance, after which a part of the weight is transferred to the armature and the upper retardation tube. It is well understood 30 by those familiar with arc lamp construction that a certain amount of movement is allowed the armature before the clutch becomes operative, and in the present lamp, this movement of the armature is sufficient to relieve slideable frame 12-13 of a part of the weight imposed thereon. Were the retardation tube 43 entirely omitted, the slideable frame when relieved suddenly of the weight of the armature would 35 fly upward suddenly, such upward movement being due to the action of springs 16, but the retardation tube 43 acts through the carbons to hold the frame 12-13 in check and imparts a steady movement thereto. 40 As showing that the upper dash pot 66 has no direct relation to or connection with the retardation tube 43, we will assume that the solenoid has lifted the armature, thereby relieving the frame 12-13 from the weight 45 thereof. The piston of dash pot 66 binds, we will say, and, therefore, rises slowly. The parts having been adjusted properly and working freely, the lower retardation tube 43 rises faster than the upper dash pot 50 66 and by so doing the lower carbon would simply push the upper carbon upwardly, said upper carbon sliding through the clutch, in which event the clutch when rendered operative by the solenoid plunger 55 would grip the carbon a little lower down. The object of holding the carbons together until there is a steady pull on the armature is secured by the action of the parts as hereinbefore indicated, and it is apparent that the slow action of the upper dash pot is of no consequence so long as said dash pot does operate. Should the upper dash pot be free to operate and the lower retardation tube bind in operation, this indicates that the lamp is out of adjustment, but this can be remedied by the means provided therefor. 70 From the foregoing description it will be understood that the clutch responds quickly to fluctuations in the strength of the current and that it operates to engage and release the carbon A, whereas the upper retardation device is always in condition for use, for the purpose of controlling the descent of the upper carbon in a slow gradual manner when the clutch is free from said upper carbon. In the operation of feeding the carbon, the clutch or the piston head are always operative, and when the clutch lets go, the piston head checks and controls the descent of the carbon so as to make it approach the lower carbon with a gradual and slow feed movement. This results in the keeping the arc steady and uniform, and it secures a light which is characterized, not only by greater luminosity, but by a freedom 80 from violet rays, the whole result being due to the fact that the full strength of the current is utilized in the production of the arc. 85 Changes in the form, size, proportion, and minor details of construction may be made without departing from the spirit of the invention or sacrificing any of the advantages thereof, and I, therefore, reserve the right to make such alterations and modifications as fairly fall within the scope of my invention, as defined by the annexed claims. 90 Having thus described my invention, what I claim and desire to secure by Letters Patent is:— 100

1. In an arc lamp, contacting upper and lower carbons, carriers therefor, means actuated by the flow of a current for raising the upper carbon, and separate means for simultaneously raising the lower carbon while in contact with the upper carbon, one of said carbons being moved relatively to the other carbon for a distance in excess of that through which the companion carbon is 115 moved and at a time subsequent to the completion of the movement of said carbons while in contact with each other, whereby the arc is struck. 120
2. In an arc lamp, contacting upper and lower carbons, carriers therefor, means for guiding the lower carbon carrier in a rectilinear path, means operated by the flow of a current for lifting the upper carbon, and separate means for lifting the lower carbon 130

simultaneously with, and at the speed of, the upper carbon, said current operated means for the upper carbon being adapted to move the upper carbon for a distance in excess of that through which the lower carbon is moved and to separate the upper carbon from the lower carbon at the completion of their simultaneous movement, whereby the arc is struck.

16 3. In an arc lamp, carbon carriers, upper and lower carbons adapted to contact with each other when no current is flowing, electrically-actuated mechanism for lifting the upper carbon and one of said carriers, and 15 mechanical devices independent of said electrically-actuated devices for making the lower carbon rise simultaneously with the upward movement of the upper carbon, said electrically-actuated mechanism being effective in moving the upper carbon for a distance in excess of the distance through which the lower carbon is moved, thereby separating the carbons subsequent to the initial conjoint movement of the two carbons.

25 4. In an arc lamp, an upper carbon carrier, a lower carbon carrier, carbons in said carriers, means for directing each carbon carrier in a rectilinear path, means for limiting the upward movement of the lower 30 carbon carrier, means operated by the flow of an electric current for moving one of the carbons and its carrier, and mechanism for moving the other carbon and its carrier in a path corresponding to that of the first 35 named carbon, said carbons moving while in contact with each other and for a predetermined distance on the initial flow of current through the lamp, one of said devices being effective in moving one carbon for a distance 40 in excess of that through which the other carbon is moved, thereby separating the two carbons subsequent to their conjoint movement, for establishing the arc.

45 5. In an arc lamp, contacting upper and lower carbons, carriers therefor, an electrically-controlled clutch for moving endwise the upper carbon, independent mechanism for moving the lower carbon while in contact with the first named carbon, thereby 50 producing a closed path through the carbons for the initial flow of current through the lamp, and means for moving the upper carbon for a distance in excess of that through which the lower carbon is moved, thereby 55 separating the carbons subsequent to their period of conjoint movement and striking the arc.

6. In an arc lamp, contacting carbons, carriers therefor, a clutch for lifting the 60 upper carbon when current is admitted to the lamp, an electro-magnet controlling said clutch, and mechanically operated devices acting on the lower carbon for causing it to follow the initial movement of the clutch-controlled upper carbon, and to remain in

contact therewith during such following movement, said electro-magnet operating to move the upper carbon a distance in excess of the distance through which the lower carbon is moved, thereby striking the arc by 70 separating the two carbons.

7. In an arc lamp, contacting carbons, carriers therefor, a clutch for raising the upper carbon when an electric current is admitted to a lamp, a frame movable in a rectilinear path, one of said carbon carriers being movable with said frame, and means acting on said frame for lifting the lower carbon and its carrier simultaneously with the elevation of the upper carbon by said clutch, whereby said carbons remain in contact with each other during their initial upward movement, said clutch operating to lift the upper carbon a distance in excess of the distance through which the lower carbon 85 moves.

8. In an arc lamp, contacting carbons, carriers therefor, electrically-operated means for lifting the upper carbon when current is admitted to the lamp, a slidable frame supporting the carbon carrier for the lower carbon, said frame and the carbon carrier therefor being adapted to be depressed by the weight of the upper carbon and a carrier therefor, and means for lifting the slidable 90 frame and its carbon carrier simultaneously with the upward movement of the upper carbon, whereby the two carbons are adapted to remain in mechanical engagement with each other and for a limited part of their 95 upward movement, said electrically operated means being adapted to lift the upper carbon for a distance in excess of the distance through which the lower carbon is moved, whereby the carbons are separated and the 100 arc is struck.

9. In an arc lamp, a lamp-frame, a foot-plate pivotally connected to a part of said lamp frame and adapted for swinging adjustment into and out of alignment with the position normally assumed by the carbons in the lamp, another frame slidable on the lamp frame, a carbon holder on the slidable frame, a retardation device carried by the foot-plate, and a separable connection between the retardation device and the slidable frame.

10. In an arc lamp, a lamp-frame, a movable member on said lamp frame, another slid- 110 able on the lamp-frame, a carbon carrier on the slidable frame, a retardation device on the movable member of the lamp-frame, and a separable connection between the retardation device and the slidable frame.

11. In an arc lamp, the combination of 125 a lamp-frame, having a movable member connected with a stationary member of said frame, another frame slidable on the lamp-frame, a lower carbon carrier supported by said slidable frame, a piston head supported 130

in a stationary position on the movable member of the lamp-frame, a movable cylinder enveloping said piston head, and a separable connection between said cylinder and the slidable frame.

12. In an arc lamp, a lamp-frame having a swinging member, a retardation device carried by said swinging member, a slidable frame supported by the lamp frame, a lower carbon carrier on said slidable frame, and a ball and socket connection between the retardation device and a part of the slidable frame, said ball and socket connection having its members united detachably.

13. In an arc lamp, a slidable frame having a lower carbon carrier, a lamp frame, a retardation device supported by said lamp-frame and a separable connection between the retardation device and the slidable frame,

20 said separable connection comprising a rotative plug provided with a stud, and a thimble having a slot adapted for the reception of said stud on the rotative plug.

14. In an arc lamp, a lamp-frame having a depending casing, a threaded stem attached to said casing, a globe holder fitted to the casing, a nut screwed on the stem and engaging with the holder for clamping it to the casing, and a dog carried by the stem and 30 cooperating with the nut for holding the latter in place.

15. In an arc lamp, a lamp-frame having tubular slotted members, a cross plate fitted slidably on the tubular members of said 35 lamp-frame, spring actuated means slidable in the slots of the tubular frame members and connected with said cross plate for imparting slidable movement thereto, a carbon holder movable with the cross plate, and a 40 current-controlled carbon holder adapted to support an upper carbon in alinement with a lower carbon which is to be supported in the holder on said cross plate.

16. In an arc lamp, a retardation tube, a piston-head therein, a carbon-carrier connected to said piston-head, a closure attached to said tube above the piston-head therein, said closure being provided with a single

air port, a single check valve in coöperative relation to said port in the closure and 50 adapted to be seated and unseated by the movement of said piston-head in the retardation tube, and an independent valve also in coöperative relation to the single port, said independent valve being adjustable relatively to the port for varying the 55 effective area of said port.

17. In an arc lamp, a retardation tube, a piston-head therein, a carbon-carrier connected to said piston-head, a closure attached 60 to said tube above the piston-head therein, said closure being provided with a single air port, a single check valve in coöperative relation to said port in the closure and adapted to be seated and unseated by the movement 65 of said piston-head in the retardation tube, a plug adjustable in said tube relative to the closure, and a regulating valve carried by said plug and disposed in coöperative relation to the aforesaid port for varying the 70 effective area thereof, said check valve and the regulating valve coöperating with the respective sides of the closure and the port therein.

18. In an arc lamp, a top plate, a retardation tube for an upper carbon, and a swiveled connection between said retardation tube and the top-plate, whereby the tube is suspended from the plate and is free to have 75 rotating adjustment relative thereto. 80

19. In an arc lamp, a top plate, a retardation tube for an upper carbon, a closure attached to said tube and lying below the top-plate, and a ball and socket connection between the top plate and said closure, where- 85 by the tube is suspended from the plate and is free to have rotating adjustment relative thereto.

In testimony whereof I have signed my name to this specification in the presence of 90 two subscribing witnesses.

FREDERICK W. GORE.
